UNITED STATES PATENT OFFICE.

ELIAS HARRY PALMER, OF CHARLESTON, SOUTH CAROLINA.

MONOTRACK TROLLEY PLANE.

1,415,190.

Specification of Letters Patent. Patented May 9, 1922.

Application filed February 14, 1921. Serial No. 444,930.

To all whom it may concern:

Be it known that I, ELIAS H. PALMER, a citizen of the United States, residing at Charleston, in the county of Charleston, State of South Carolina, have invented new and useful Improvements in Monotrack Trolley Planes, of which the following is a specification.

This invention relates to mono-track trolley planes, and particularly to a machine adapted and intended for conveying passengers, freight, and the like.

An object of my invention is to provide a machine combining the advantages of a track and trolley vehicle with those of aeroplane navigation, and at the same time eliminating the disadvantages of the one and the hazards of the other.

A further object resides in constructing a machine with an aerial propellor drive and using an electric motor as the power unit, with current supplied from a distant source, thus lessening the cost of construction and maintenance and increasing the load carrying and travelling capacities of the machine.

Another object lies in providing a track upon a set course of travel and so constructing the machine that at low speeds it will travel upon said track whereas when higher speeds are attained planes embodied in the machine will support the weight and the machine will travel at an elevation slightly raised from the track.

With these and other objects in view, which will be apparent from the drawings, specification and claims, this invention includes certain novel features of construction and combinations of parts which will now be set forth.

40 In the drawings:

Figure 1 is a view in elevation showing one adaptation of my invention.

Fig. 2 is a view in front elevation with the track shown in section.

45 Fig. 3 is a longitudinal sectional view through the body of the machine.

Fig. 4 is a transverse sectional view through the track and a portion of the body to better show the trolley.

50 Fig. 5 is a perspective view illustrating the brake structure by which movement of the car along the track is controlled and stopped.

The track 1 is supported upon the ground or is elevated on pillars or posts 2, to any desired height above the ground. The track

1 consists of spaced side bars 3 and 4 held in position by cross bars 5 and having plates 6 and 7 secured on their upper edges to overhang inwardly and leave a narrow trolley slot.

Wires 8 and 9 are mounted on the inner faces of side bars 3 and 4, and these wires are connected with a suitable generator 10, or to receive electric current from any other desired source, the wires 8 and 9 being left as unconnected leads extending throughout the length of the track 1.

The car of the machine consists of a body 11 which is provided with a longitudinal central groove or channel 12 to fit over the track 1, the body overhanging at each side and being made to a sufficiently close fit to hold against lateral displacement and to give side support. The body is balanced upon the track and is supported to travel thereon by wheels 13 and 14 which ride upon the side bars 3 and 4. If desired these wheels may be provided with ball bearings and rubber tires, or they can be constructed in any other way to add to the smoothness of operation of the car.

The body 11 is given a stream line shape much after the design of an aeroplane fuselage, and has a seat 15 at the forward end for the operator. This body may be enclosed or open and can be divided off to give seating capacity or to provide freight compartments. One or more planes 16 are provided extending laterally from the body after the manner of an aeroplane and it may be desirable to provide a tail structure at 17 similar to the tail structure of aeroplanes.

At the forward end of the body an electric motor 18 is mounted by bearing trunnions 19 with its shaft disposed horizontally, a rack 20 and a worm 21 turned by a hand wheel 22 within reach of the operator's seat 15 being provided to shift the motor to elevate and lower the forward end of the motor shaft. A propellor 23 is mounted on the forward end of the motor shaft, and will be raised and lowered as the motor is rocked by manipulation of hand wheel 22.

A bearing sleeve 24 is mounted centrally within the body 11 and a trolley housing 25 is slidable therethrough, the arrangement of these parts being best shown in Fig. 4. The trolley housing extends through the trolley slots of the track 1 and has contact shoes 26 and 27 carried at its lower end in sliding contact with the wires 8 and 9. Rollers

28 and 29 are provided on the trolley housing to travel against the under sides of the overhanging portions of plates 6 and 7. The circuit wires 30 and 31 connected with shoes 5 26 and 27 are led to the motor 18, a switch 32 being provided for control of this circuit. The housing 25 is slidable through bearing sleeve 24 and a spring 33 is provided to hold the trolley housing in the 10 proper elevation.

To control the speed of travel and to stop movement of the car along the track a brake structure such as shown in Fig. 5 may be used. In this adaptation the shafts 34 are 15 mounted through the bottom of the body on opposite sides of the track and have brake shoes 35 on their lower ends, springs 36 being provided to normally hold the shafts in a position that the brake shoes 35 are out of 20 contact with the side rails of the track. The foot pedal 37 is connected with arms on shafts 34 to permit the operator to turn the shafts against the tension of springs 36 and bring the brake shoes into frictional bearing 25 against the outer sides of the rail of the track.

In the use of my invention current is supplied from generator 10 to the wires 8 and 9 and when the switch 32 is closed the propeller 30 23 is revolved. The brakes are released and the propeller moves the car forward upon rollers 13 and 14. As speed of twenty-five or thirty miles an hour is attained the planes 16 will take the weight of the machine 35 from the wheels travelling on the track, the planes acting also to stabilize and give lateral support to the car. By turning hand wheel 22 the operator rocks the motor 40 to swing the propeller so that its turning axis is angularly above or below the horizontal and in this way the car is maintained in proper proximity, between four and ten inches above the track. Spring 33 acts to hold the trolley housing in a proper 45 elevation and the housing and wheels 28 and 29 aid in maintaining the proper position of the car. The speed of travel can be regulated through the motor and as the speed is cut down to below that at which the planes 50 16 sustain the load the weight of the machine will again ease down upon wheels 13 and 14. The brake structure can be manually manipulated to control and stop movement of the car.

55 While, in the foregoing, I have described specific embodiments, and have mentioned only certain possible modifications, it will be appreciated that in practice I do not limit myself to such specific details as herein set forth, but may resort to any practical modifications falling within the scope of the invention as defined in the appended claims.

I claim:

60 1. A mono-track trolley plane including with a track having an electric circuit ar-

ranged therewith, a car having supporting planes and adapted to travel upon and at an elevation above said track, a propeller, and an electric motor receiving current from the circuit wires of the track by which said propeller is turned. 70

2. A mono-track trolley plane including with a track having an electric circuit arranged therewith, a car having supporting planes and adapted to travel upon and at an elevation above said track, a propeller, an electric motor receiving current from the circuit wires of the track by which said propeller is turned, and means to shift said propeller to turn on an axis angularly above and 75 below a horizontal line.

3. A mono-track trolley plane including with a track having trolley wires extending throughout the length thereof and receiving electric current from a suitable source, a car 85 having planes associated therewith provided with a longitudinal groove to receive the track, a trolley structure carried by said car and having shoes engaging with the trolley wires, an electric motor in the car to which 90 wires are led from said shoes, a propeller mounted on the shaft of said motor, and means to shift said propeller to turn on an axis angularly above and below a horizontal line. 95

4. A mono-track trolley plane including with a track having trolley wires extending throughout the length thereof, a car having supporting planes and adapted to travel upon and at an elevation above said track, an electric motor mounted on the car, a trolley in contact with said trolley wires and having circuit wires leading to said motor, an aerial propeller mounted on the motor shaft to impart movement to said car to carry the same 100 along the track, and a brake mounted on the car engageable with said track to control the speed and to stop travel of said car. 105

5. A mono-track trolley plane including with a track having trolley wires extending 110 throughout the length thereof, a car having supporting planes and adapted to travel upon and at an elevation above said track, an electric motor mounted on the car, a trolley in contact with said trolley wires and having 115 circuit wires leading to said motor, an aerial propeller mounted on the motor shaft to impart movement to said car to carry the same along the track, means to shift said propeller to turn on an axis angularly above and below 120 a horizontal line, and a brake mounted on the car engageable with said track to control the speed and to stop travel of said car. 125

6. A mono-track trolley plane including with a track comprising a pair of spaced side bars having trolley wires extending throughout the length of their inner faces and receiving electric current from a suitable source, a car grooved longitudinally to fit upon and overhang at each side of said track, wheels by 130

which said car is supported upon the track for movement along the length thereof, planes extending laterally at the sides of the car, a trolley carried by the car and in contact with the wires of said track, a motor mounted on the car and having circuit wires from said trolley connected therewith, and a propeller mounted on the motor shaft.

7. A mono-track trolley plane including 10 with a track comprising a pair of spaced side bars having trolley wires extending throughout the length of their inner faces and receiving electric current from a suitable source, a car grooved longitudinally to fit upon and 15 overhang at each side of said track, wheels by which said car is supported upon the track for movement along the length thereof, planes extending laterally at the sides of the car, a trolley carried by the car and in contact with the wires of said track, a motor 20 mounted on the car and having circuit wires from said trolley connected therewith, a propeller mounted on the motor shaft, and means to rock said motor to swing the propeller to 25 turn on an axis angularly above and below a horizontal line.

8. A mono-track trolley plane including 30 with a track comprising a pair of spaced side bars, plates mounted on the upper edges of said side bars to overhang on the inner sides

thereof and spaced to provide a trolley slot, trolley wires mounted on the inner side of each of said side bars and connected with a suitable electric current supply, a car having a longitudinal groove mounted upon said track to overhang on each side thereof, bearing rollers on said car spaced to travel on the side bars of said track to support the weight thereof and leaving the car free to rise above the track, planes extending outwardly at the 40 sides of the car, an electric motor given swinging mounting within the car with its shaft disposed horizontally, an aerial propeller mounted on the motor shaft, means to rock the motor to shift said propeller to turn 45 on an axis angularly above and below a horizontal line, a bearing sleeve mounted centrally within the car, a trolley housing received slidably through said bearing sleeve and extending through the trolley slot of the 50 track, trolley shoes carried by said trolley housing in sliding contact with the trolley wires, circuit connections from said trolley shoes to the motor, and roller carried by said trolley housing in bearing engagement with 55 the under sides of the overhanging plates of the track.

In testimony whereof, I affix my signature.

ELIAS HARRY PALMER.
